7200X Stephen Ustick
Improvement in Saws -

The Schedule referred to in their Letters Patent and
making part of the same containing a description in the words of
the said Stephen Ustick himself of his improvement in saws.

To all to whom these Presents shall come

Be it Known, That I Stephen Ustick of Washington
City in the county of Washington, District of Columbia, have
invented a new and useful improvement in Saws, and that the
following is a full and exact description of the construction
and operation of said improvement as invented by me -

This improvement in the first place consists of two
subdivisions of teeth, which I call side cutters of the following
form and position. These are round at their ends instead of
pointed, filed to an edge on the end, every other one contrarywise
so that each side of the saw, has to it an equal number of the
flat sides of them, and are larger than the other teeth so that
there is always a cut on each side of them to prevent the
resistance to their sides which is occasioned to other saws.
The side cutters are made of teeth set each other only two
being together one to each row. Between each pair there is a
number of teeth of the common construction. In some ^{useful} saws
and for or of cutting there should be as many of the cutters
as there are other teeth, but in saws used chiefly as all together
for ripping, but a small proportion of them is required. The
cutters are set of the same height as the other teeth.

The improvement in the second place consists in the
outside of the teeth being made perfectly parallel to a line
a little below the points of the lower teeth to effect smooth
or level cutting.

This improvement operates to effect a surface much
smoother & more level and to produce a much greater
